UNITED STATES PATENT OFFICE.

GEORGE W. HAURY, OF CHICAGO, ILLINOIS.

GAS-ENGINE SLIDE-VALVE MECHANISM.

1,247,109.

Specification of Letters Patent. Patented Nov. 20, 1917.

Application filed September 7, 1915. Serial No. 49,142.

To all whom it may concern:

Be it known that I, GEORGE W. HAURY, a citizen of the United States, residing at Chicago, in the county of Cook and State of Illinois, have invented certain new and useful Improvements in Gas-Engine Slide-Valve Mechanism, of which the following is a specification.

My invention relates to slide-valve gas engines. Among its objects are to promote efficiency and attain silence in engine operation; to provide a simple and economical valve construction with positively operated slide-valves; to arrange the valve structure so that its movable parts are free from wearing engagement with the piston of the engine and from direct action of the ignited charges; to construct and locate the valve structure axially beyond the engine-frame proper for ready accessibility and removability of parts; and to provide a construction in which the valve mechanism is made gas tight by simple and adequate means.

25 In the drawings;

Figure 1, is a central vertical section through a fragment of a multiple cylinder engine, taken on line 1—1 of Fig. 2;

Fig. 2 is a horizontal section taken on line 30 2—2 of Fig. 1.

Fig. 3 is a vertical section on line 3—3 of Fig. 1, and;

Fig. 4 is a detail of the two-part slide annulus.

35 The gas engine 10 may be of the usual four-cycle construction in general, and may embody any desired number of cylinders 11. Any suitable mechanism, fragmentarily indicated by gearing, 13, may be employed 40 to drive a valve-actuating shaft 14, in one-to-two relation to the engine crank shaft. Such valve-shaft 14 is located beyond the cylinders and is demountably carried in suitable split bearings 15. The properly 45 timed cranks 16 separately actuate all of the valves.

A demountable, valve-carrying engine-head 17, together with a protective casing for the moving parts, is secured in place on 50 the engine by bolts 19. The casing 18 is preferably recessed as at 20 to receive the bolt heads or nuts, and the top of the cover or casing is preferably made separate and bolted on as at 21 to give easy access to the 55 valve parts.

For each cylinder the engine-head pro-

vides a combustion chamber 22 opening axially to the engine cylinder, and closed at its outer end 23. In the walls of the head are made longitudinal slide ways 24, and in them slide the two valves 25 and 25' that respectively control the intake and exhaust ports for the cylinder. The ports or openings 26 and 26' of said respective valves preferably have their external 65 mouths at a higher level than their internal mouths, to facilitate the gas-tight packing, and each such valve opening controls its appropriately located intake port-couple 27 or exhaust port-couple 27' made at proper 70 levels in the walls of the slide-way. The two valves, axially reciprocated independently by links 28 and 28' that are detachably pivoted to the valves and that connect the suitable cranks of the shaft 14, therefore 75 respectively control the introduction and ejection of the fuel and exhaust gases.

More specifically the engine-head 17 may best provide, in a single casting, the annular walls or shells 30 for the several valve-mechanisms, the flanges 31 that form the bottoms of slide spaces 24, the piping stubs 32 and 32' that respectively connect the intake and exhaust ports with the manifolds 33 and 33', and the water jacket 34 for the 85 entire head. Each said flange 31 receives the reduced end of a valve-cylinder 35, that is locked in place by a suitably packed nut 36. Thus the slide space 24 between the concentric walls 30 and 35 is annular in section. Of course the diameter and depth of the combustion chamber 22 within the valve cylinder 30 may be varied to give just the desired compression-area, but generally the diameter is made less than that of the engine cylinder 11, to provide a reduced bore extension of the cylinder area and the spark plug 38 is generally located centrally in the end wall 23 of such space. Suitable packing-rings 39 carried by the head walls 30 and 35 above and below the ports make gas tight fit with the slide valve members 25 and 25'. The two valve members 25 and 25' of each pair interlock slidably at their meeting edges so that jointly they form an annulus rigid against radial displacement of its parts.

This interlocking joint is preferably made as shown in Fig. 2 by forming dove-tail tenons and mortises 40 and 40' along the engaging edges of the respective members.

I prefer that the spacing between a raised

crank of the valve-crank shaft and the cylinder-head 23 shall be greater than the length of the valve member so that any valve member may be axially removed subsequently to its disconnection from its link 28 or 28'. Or, if this distance be shortened, to less than such clearance removal of the valves may be accomplished by preliminary removing the crank shaft from its split 10 bearings.

It will be understood, of course, that the crank will be properly timed to cause valve operation during the proper cycles of engine rotation and in proper sequence according 15 to the number of cylinders employed.

Many advantages of slide valve construction are generally recognized, as evidenced by adoption of the "knight" engine. My invention retains such salient advantages 20 as positive action, silence, and durability; reduces the number of parts and simplifies the construction; assures application of the explosive force directly along the line of piston displacement for engine efficiency; 25 removes the moving parts of the valve from direct action of the gases and from contact with the cylinder, so that the fitting of the valve may be independent of piston-fit; enables individual valve elements to be re- 30 moved and replaced with minimum labor; and admits of the application of the slide valve structure to already-built engines in lieu of the usual puppet-valve-carrying head.

35 Other advantages will be apparent to those skilled in the art, and it will be obvious that while I have herein described in some detail a particular embodiment of my invention for purposes of full disclosure of 40 one form thereof, changes in construction may readily be made without departing from the spirit of my invention.

What I claim is;

45 1. A gas engine valve mechanism, comprising a head attachable to the end of an engine cylinder, said head containing an extended water jacket space, intake and exhaust stubs and having a centrally positioned cylindrical opening therein, a tubular shell positioned within said opening and spaced from the walls thereof, means for securing the tubular shell to the head, longitudinally reciprocal valve members slid- 50 ingly controlling ports formed in said head and tubular shell, means carried by the head for reciprocating the said valve members, and means independent of the tubular shell for attaching the head to the engine cylinder.

60 2. An engine valve mechanism comprising longitudinally slidable ported valves, said valves jointly forming an annulus and having their edges interlocked against radial displacement but slidable relative to each 65 other.

3. Gas engine valve mechanism comprising a structure having parallel annular ported walls surrounding a combustion chamber and longitudinally slidable ported valves in the space between said walls, said valves jointly forming an annulus and having their edges interlocked against radial displacement but slidable relatively to each other. 70

4. Gas engine valve mechanism comprising a structure having parallel annular ported walls surrounding a combustion chamber and longitudinally slidable ported valves in the space between said walls, said valves jointly forming an annulus and having at 80 their edges coacting dove-tailed mortises and tenons preventing radial separation of the valves but leaving them free for independent longitudinal movement. 75

5. A slide-valve head comprising a shell 85 having an internal bottom flange, a ported cylinder closed at one end and at its open end reduced and seated on said flange, means carried by the lower end of the cylinder for securing the shell and cylinder in fixed relation to each other, and longitudinally slid- 90 able ported valve-members in the interspace between the shell and cylinder. 95

6. A slide-valve head comprising a water-jacketed, ported shell having an internal 95 bottom flange, a ported cylinder closed at one end and at its open end reduced and seated on said flange, means carried by the lower end of the cylinder for securing the shell and cylinder in fixed relation to each 100 other, and longitudinally slidable ported valve-members in the interspace between the shell and cylinder. 105

7. A slide-valve head comprising a ported shell having an internal bottom flange, a 105 ported cylinder closed at one end and having its lower end reduced to fit within said flange and fixed thereto; and ported sliding valves in the space between said cylinder and shell, having their meeting edges in- 110 terlocked against radial separation. 110

8. A slide-valve head comprising a ported shell having an internal bottom flange, a ported cylinder closed at one end and having its lower end reduced to fit within said 115 flange and fixed thereto; and ported sliding valves in the space between said cylinder and shell, having their meeting edges interlocked against radial separation, by dove- 120 tail grooves and tenons in the respective parts. 120

9. A gas engine valve mechanism comprising a head attachable to the end of an engine cylinder and having a central cylindrical opening therein with an internal 125 bottom flange, a ported cylinder closed at one end and at its open end reduced and seated on said flange, an annular ring of an external diameter equal to that of the engine cylinder internally threaded for en- 130

gagement with the threaded lower end of the ported cylinder to clamp the same in fixed relation with respect to the head, and longitudinally slidable ported valve members in the inner space between the walls of the cylindrical opening and the ported cylinder.

5 In testimony whereof I hereunto set my

hand in the presence of two subscribing witnesses.

GEORGE W. HAURY.
